UNITED STATES PATENT OFFICE

91,003

DESIGN FOR AN ADVERTISING DISPLAY STAND

James L. Younghusband, Chicago, Ill.

Application August 16, 1933. Serial No. 49,042

Term of patent 3½ years

To all whom it may concern:

Be it known that I, JAMES L. YOUNGHUSBAND, a citizen of the Dominion of Canada, residing at Chicago, in the county of Cook and State of Illinois, have invented a new, original, and ornamental Design for Advertising Display Stand, of which the following is a specification, reference being had to the accompanying drawing, forming a part thereof.

The figure is a perspective view of my advertising display stand showing my new design.

The upstanding containers are integral parts of my advertising display stand.

I claim:

The ornamental design for an advertising display stand substantially as shown and described.

JAMES L. YOUNGHUSBAND.
